PUMPING APPARATUS

Norman Eugene Dell, Buffalo, N. Y.

Application January 7, 1938, Serial No. 183,753

1 Claim. (Cl. 103—161)

An object of my invention is to provide an apparatus for creating either fluid or gas pressures and wherein the pump is contained within a tank which also contains a fluid or gas, such as air and water, under pressure, and whereby through the actuation of the pump, the water or air can be drawn off under pressure.

A further object of my invention is to direct fluid such as water under a low pressure into the pump, and through the actuation of the pump in the tank to deliver the water into the tank under a greatly increased pressure.

A still further and important object of my invention is to construct my pump with a plurality of rotatable radially extending pistons and cylinders, and wherein the pistons are reciprocated by an eccentric ring guide which surrounds their axis of rotation, and wherein the pressures at both ends of each piston are equalized at certain portions of the piston's travel around the eccentric ring, as shall be hereinafter explained.

With these and other objects in view, my invention consists of a pumping apparatus constructed and arranged all as hereinafter more particularly described and illustrated in the accompanying drawings, in which:

Figure 1 is a transverse cross-sectional view through my tank and pump, being taken through the line 1—1, Figure 2.

Figure 2 is a longitudinal sectional view through the tank and pump, being taken through the line 2—2, Figure 1.

Figure 3 is an enlarged cross-sectional view through one of the rotatable cylinders and pistons of the pump, being taken through the line 3—3, Figure 1.

Figure 4 is an enlarged cross-sectional view through the portion of the eccentric guide indicated by the line 4—4, Figure 1, one of the piston shoe assemblies being shown as at that point.

Figure 5 is a similar view of Figure 4, being taken through the line 5—5, Figure 1, and.

Figure 6 is an enlarged longitudinal cross-sectional view through a fragmentary portion of the cylinder head and piston contained therein showing the piston engaging the outlet valve and holding it open during the portion of its movement at the inner end of its stroke.

Like characters of reference indicate corresponding parts in the different views of the drawings.

The apparatus comprises a tank 1 which can be of any suitable construction, and as shown in the drawings, is of cylindrical form with its

axis horizontal. The tank is provided with an upper outlet pipe 2 for drawing off air and a lower outlet pipe 3 for drawing off water. The tank is also furnished with upper and lower feed pipes 4 and 5 through which the air pressure or water level may be built up within the tank from outside sources in cases where the constant pressure, which should be maintained at all times in the tank, has been allowed to drop.

In the present illustration I have only shown one pump structure within the tank, but it is to be understood that a battery of pump structures may be contained within a single tank. The pump structure, as illustrated, consists of four cylinders 6 which are open at their inner ends and radiate from a hollow boss structure 7. The boss structure 7 is divided into two open ended chambers 41 and 42 by a transverse partition 43. The chamber 41 is secured upon the end of a hollow rotatable shaft 8 which protrudes from the end 9 of the tank through a suitable air-tight stuffing box 10. The protruding end of the shaft 8 carries any suitable type of driving mechanism such as a gear wheel 11 meshing with a driving pinion 12. I also show the hollow shaft 8 supported within a bearing 13. The outer end of the shaft 8 is in communication with a fluid feed pipe 14 which is, of course, stationary. Any suitable type of fluid-tight connection can be made between the pipe 14 and the rotatable hollow shaft 8, and in the drawings I have shown the end of the pipe 14 formed with a flange 15 which is in turn rotatably contained within a ring shaped housing 16 carried upon and rotatable with the shaft 8. Suitable packings 17 are inserted between the sides of the flange 15 and the inner side faces of the housing 16.

The rotatable cylinders 6 are contained within a stationary housing which is in turn contained within the tank. Such housing consists of a pair of end plates 18 which are positioned upon either side of the path of rotation of the cylinders 6 and are provided with central hubs 19 through which the shaft 8 extends and within which the shaft rotates. The peripheral portions of the end plates 18 are secured to a ring-like eccentrically shaped cam member 20 in any suitable manner, such as by bolts 21, and the assembly of the eccentric ring 20 and end plates 18 is rigidly retained in place by suitable brackets 22 which are secured to the inner face of the tank 1.

Each of the rotatable cylinders 6 contains a reciprocating piston 23 which projects from the outer end of its cylinder. The outer end of each piston carries a shoe 24 which is pivotally secured

to a boss 25 formed upon the end of the piston. Each shoe 24 has a curved outer face 26 of the same curvature as a portion of the eccentric ring 20 as shall be hereinafter explained, and each 5 shoe also carries two pairs of freely rotatable rollers 27, which engage certain portions of the eccentric ring 20 as shall also be hereinafter explained.

The rotatable boss portion 1 on the hollow shaft 8 carries four pairs of inlet and outlet mushroom valves 28 and 29, a pair of inlet and outlet valves communicating with each cylinder 6. The inlet valves 28 open from the chamber 41 into the cylinders, and the outlet valves 29 open from the cylinders into the chamber 42. The valves are contained within suitable cages 30 and 31 which are threaded into orifices in the hub 7. Each inlet valve 28 is actuated by the fluid pressure entering from the hollow shaft 8, 20 and each outlet valve 29 is actuated by the fluid pressure created in its cylinder 6 under the downward movement of its piston 23. When the pistons 23 are moving outwardly in the induction strokes, the inlet valves 28 are sucked open and 25 the outlet valves 29 are sucked closed. When the pistons 23 are moving inwardly in the eduction strokes, the inlet valves are pressed shut on their seats under the fluid pressure in the cylinders and the outlet valves are opened under the 30 fluid pressure in the cylinders. In order that the tank air pressure be admitted to the pump casing formed by the end plates and eccentric ring 20, shielded orifices 32 are provided in the end plates 18. A hollow shaft 58 extends from the chamber 42 and has its outer end 33 rotatably 35 contained within a stationary elbow 34 carrying a downwardly extending delivery pipe 35 which has its lower open end submerged in the water in the tank 1.

The eccentric ring 20, which is preferably of 40 a shape substantially the same as that shown in Figure 1, is constructed in the following manner. The portion 36 of the ring extending in a clockwise direction from the point A to the point B, has a pair of raised tracks 38, one on each side 45 of the ring as shown in Figure 4, upon which the rollers 27 will roll when the shoes are travelling from point A to point B, such tracks being raised sufficiently above the face of the ring to lift and retain the face of the shoes 24 out of 50 contact therewith. At the point B on the ring 20, the tracks 38 merge into the same level as the face of the ring between the tracks so that the face of the shoes 24 at this point move into 55 engagement with the face of the ring. Just past the point B on the ring, the tracks 38 decline below the face of the ring, as illustrated in Figure 5, so that the rollers are out of engagement with the tracks and the shoes are in sliding 60 engagement with the face 39 of the portion 37 of the track.

The portion 37 of the ring extends from the point B to the point A in a clockwise direction and the face 39 extends between these two 65 points. The face 39 is ground to the same curvature as the faces 26 of the shoes, the reason for which will be made apparent.

At the point A in the ring, the tracks 38 gradually rise above the central portion 39 so that 70 the rollers 27 on the shoes in passing the point A again come into contact with the tracks 38 lifting the faces 26 of the shoes away from the face 39 of the ring. The lower portion of the pump casing contains a reservoir of oil through 75 which the outer ends of the cylinders and pistons

move and also through which the shoes 24 travel. Such oil level is indicated in Figure 1. The faces of the shoes in passing through the reservoir, become coated with oil which, as the faces 26 move into engagement with the face 39 of the ring, is scraped to a very thin film between the two faces, resulting in the adhesion of the face 26 of the shoes to the face 39 of the portion 37 of the ring 20.

In order that the faces 26 of the shoes 24 may 10 slide into tight adhesion with the face 39 of the ring 20 as they slide thereonto, I form each outlet mushroom valve 29 with an extra stem 59 which is momentarily engaged by the head of the piston during the inner portions of the piston's 15 compression stroke, as illustrated in Figure 6, so that the fluid pressure in the cylinder will not be cut off until the face 26 has moved into engagement with the face 37, thus maintaining the pressure the same at both ends of the piston 20 and permitting the shoe to move into engagement with the face 39 by gravity. As the cylinders further rotate, the pistons move outwardly in the cylinders and pass out of engagement with the stems 59 of the valves, so that the valves 25 then close and cut off connection between the tank fluid pressures and the cylinders.

The operation of my device is as follows:

It is to be assumed that the tank 1 contains a fluid such as water substantially up to the 30 level indicated in the drawings, and that the air pressure in the portion of the tank above the water is fifty pounds, and also that a constant pressure of water at five pounds is fed from the supply pipe 14 into the hollow shaft 8 from where 35 it can pass through the inlet valves 28 into the respective cylinders 6. The gear wheel 11 and the hollow shaft 8 are continuously rotated by any suitable source of power, and as the cylinders 6 are carried upon the boss structure 1 which is 40 mounted upon the end of the shaft 8, the cylinders are continuously rotated by the source of power. Upon reference to Figure 1, it will be seen that the shape of the eccentric ring 20 is 45 such that the portion of the ring from the point B in a clockwise direction to substantially the point A of the ring is of such a curvature that the pistons 23 can move outwardly from the position of the left-hand horizontal piston to the position of the vertical upper piston. 50

Referring to Figure 1, the lower vertical piston is shown as just completing its eduction stroke and about to commence its induction stroke. In this position the lower vertical piston will be holding the exhaust valve 29 open in the manner 55 previously explained and the pressure on both ends of the piston will be equalized so that gravity will act on the piston so that the face 26 will slide into tight engagement with the face 37 at the point B. It will be noted that in traveling from the position shown to the point B, the lower vertical piston will be lubricated and as the face 26 of the lower horizontal shoe comes into engagement with the face 39, the surplus oil will be wiped off the face 26 leaving only a very thin 65 film of oil which causes the face 26 to adhere to the face 39.

The left-hand horizontal piston is shown in the position at the commencement of the induction stroke, and has travelled in a clockwise direction 70 from the position of the lower vertical piston. The left-hand horizontal piston has the face of its shoe in close sliding adhesion with the face 39 of the portion 37 of the eccentric ring. The portion 37 of the eccentric ring is shaped so that the 75

piston can be moved outwardly to the full limit of its induction stroke. On the induction stroke the inlet valve is opened and the liquid is drawn into the portion 40 of the cylinder. The induction stroke is not completed until the left-hand horizontal piston has reached the point A, travelling in a clockwise direction.

In the matter of illustrating the adhesion between the face 26 of the shoe 24 and the face 39 of the ring, an illustration is provided by placing a block of metal having a perfectly flat lower face upon a perfectly flat oiled surface. The adhesion of the oil film to the under surface of the block and to the flat surface is sufficient to prevent the block from being manually lifted up from the face of the oiled surface, although the block can be freely slid anywhere over such surface.

The outward movement of the piston will continue until that particular piston reaches the point A on the ring 20 at which point the raised side tracks 38 commence. When the shoe reaches this point the lower portion 40 of the cylinder will be full of water. As the face 26 of the shoe 24 of the piston moves into contact with the raised side track 38, the adhesion between the outer face 26 and the face 39 of the ring 20 will be broken and the face 26 will be moved away from the face 39. The pressure in the tank which enters into the pump casing 18 through the orifice 32 will still be fully effective against the face 26 of the shoe as well as against other parts of the shoe and piston which are exposed to the tank pressure. Through the force of gravity, the piston will move inwardly until the pressure in the liquid in the portion 40 of the cylinder has been raised to the pressure in the tank.

As the cylinder is further rotated in a clockwise direction, the contour of the ring 20 from the point A to the point B is such that the piston is moved inwardly to the bottom of its stroke, through the position illustrated by the right-hand horizontal piston in Figure 1 to the position of the lower vertical piston. At this point the water from the lower portion of the cylinder has been expelled into the tank. As the cylinder and its piston assembly moves in a clockwise direction from the position of the lower vertical piston shown in Figure 1 to the point B on the ring, its shoe moves into slidable adherence with the face 39 of the ring and the piston then starts to move outwardly as illustrated by the left-hand horizontal piston in Figure 1, and the cycle is repeated. Each cylinder and piston assembly has the same cycle in its rotation within the eccentric ring 20.

It will be seen from the foregoing description that on the eduction stroke of the piston that, since the pressure within the portion 40 of the cylinder is the same as the pressure within the tank, that only sufficient power will be required to

raise the pressure of the fluid within the portion 40 to cause the exhaust valve to open and overcome the inertia of the contents and the friction of the pipe-line leading to the tank so that the contents will flow thereto.

It therefore follows that the useful absorption of power from the drive shaft for each piston occurs when it is pulled outwardly against the pressure within the stationary housing and not when the piston is urged inwardly, the latter movement being effected by gravity and serving only to transfer the fluid from the cylinder to the tank.

From the foregoing description it will be seen that I have provided a structure wherein a plurality of pistons and cylinders rotate within an eccentrically shaped ring, and wherein the shape of such ring actuates the pistons within the cylinders as the piston and cylinder structure rotates, and that by enclosing the pumping mechanism within the pressure tank a very simple and effective structure has been obtained. While I have shown a certain embodiment of my invention, it is to be understood that I can make such changes and alterations as I may at any time deem necessary without departing from the spirit of my invention as set forth in the appended claim.

What I claim as my invention is:

In a pumping apparatus, a tank containing water in the bottom portion thereof and air under pressure in the upper portion thereof, a pump housing contained within the tank and from which the water is excluded, a fluid inlet pipe entering the tank and also the housing, a plurality of radially extending cylinders mounted for rotation about the pipe in the housing and communicating with the pipe, a second pipe communicating with the cylinders and extending from the housing into the tank, a piston contained within each cylinder, a piston actuating cam ring surrounding the path of rotation of the cylinders, a pair of annular tracks formed on the inner face of the cam ring, said tracks being at different levels on one portion of said cam ring and one of said tracks having a smooth oiled surface, a shoe carried on the outer end of each piston and having a smooth oiled surface adapted to engage the oiled surface track in slidable adhesion during the portion of each piston's rotative travel when it is moving outwardly in its cylinder a roller also carried on the outer end of each piston and engaging the other track during that portion of each piston's rotative travel when it is moving inwardly in its cylinder, fluid inlet valves controlling communication between the fluid inlet pipe and the cylinders, and fluid outlet valves controlling communication between the cylinders and the tank.

NORMAN EUGENE DELL
